UNITED STATES PATENT OFFICE.

JULIUS GUTMANN, OF BERLIN, GERMANY.

BUTTONHOLE-SEWING MACHINE.

SPECIFICATION forming part of Letters Patent No. 615,165, dated November 29, 1898.

Application filed October 24, 1896. Serial No. 609,955. (No model.)

To all whom it may concern:

Be it known that I, JULIUS GUTMANN, a subject of the Emperor of Germany, and a resident of Berlin, Germany, have invented 5 certain new and useful Improvements in Buttonhole-Machines, (for which I have obtained a patent in Germany, No. 87,081, dated April 23, 1895; in France, No. 253,448, dated January 25, 1896, and in Hungary, No. 5,586, 10 dated February 29, 1896,) of which the following is a specification.

My invention has relation to buttonhole-sewing machines and to the mode of barring or staying one or both ends of a buttonhole 15 to prevent such ends from fraying and tearing.

It has heretofore been the general practice to form the staying or barring stitches (hereinafter referred to as the "barring-stitches") 20 parallel or substantially parallel with the edge or binding stitches, (hereinafter referred to as the "binding-stitches.") I have discovered that the ends of a buttonhole may be more effectually and more durably barred 25 by forming the barring-stitches at substantially right angles to the binding-stitches or parallel or substantially parallel with the length of the buttonhole or by forming the barring-stitches as described and interlocking 30 some of them with the binding-stitches.

My invention has for its object mechanism for barring one or both ends of a buttonhole by means of stitches formed at or substantially at right angles to the binding-stitches 35 and parallel or substantially parallel with the length of the buttonhole or by forming said barring-stitches as described and interlocking some of them with some of the binding-stitches.

40 In the accompanying drawings I have shown a machine more particularly adapted to bind and bar both edges and ends of a buttonhole successively—that is to say, to first bind one edge, then bar one end, then bind 45 the other edge, and finally bar the other end of such buttonhole. The mechanisms for effecting these operations by imparting to the stitch-forming appliances and to the work support or holding devices the required movements operate automatically and alternately 50 whether one or both ends of a buttonhole are to be barred, and the movements of said mech-

anisms are controlled by those of a single main driving-shaft.

Although the machine is organized to bar 55 both ends of a buttonhole, it is equally adapted to bar but one end of a buttonhole, yet by the omission of certain of the operative devices and by varying the dimensions of others the machine will be so organized as to bar 60 one end of a buttonhole only.

Referring now to the drawings, Figures 1, 2, 3, and 4 are diagrammatic views illustrating the various modes of barring buttonholes, Figs. 1 and 2 showing a buttonhole barred at 65 both ends 3 and 3^a, some of the barring-stitches interlocking some of the binding-stitches 2 2^a at opposite edges of the buttonhole, and Figs. 3 and 4 showing similar views of a buttonhole barred at one end only. Fig. 70 5 is a side elevation, partly in section, of a buttonhole-machine constructed in accordance with my invention. Figs. 6 and 9 are under side views of the bed-plate, some of the mechanism being removed in the last-named figure. Fig. 7 is a front view of the machine-head with the front cover-plate removed, a like view of the work-clamp, and a cross-section of the bed-plate through the work-plate and the feed-plate therefor. Fig. 80 8 is a top view of the bed-plate, partly in section. Fig. 10 is a plan view of a portion of the work-clamp and of the mechanism for reciprocating the same in the formation of the barring-stitches. Fig. 11 is a sectional side 75 view thereof. Fig. 12 is a plan view of the main actuating ratchet-wheel, the mechanism for imparting to the work-holder a progressive or feed movement in the formation of the binding-stitches, and a part of the 80 mechanism for throwing the feed devices out of operation; and Fig. 13 is a sectional side elevation thereof.

Referring to Fig. 5, G indicates the bed-plate of a buttonhole-sewing machine, S² its 95 standard, M' the overhanging arm, and M the head on said arm, all of a construction suited to the operative mechanisms supported thereby. B is the needle-bar, w the main driving-shaft, and C the crank connection between said 100 shaft and needle-bar, such shaft carrying at its rear end a gear-wheel r and the usual cord and hand or fly wheel W.

I will now describe the several groups of

coöperative mechanisms in the order in which they come into operation to effect, first, the binding of one edge of a buttonhole, then the barring of one end, and next the binding of 5 the opposite edge or the binding of said edge and the barring of the opposite end of such buttonhole.

Any suitable lower thread-feeding mechanism may be employed, and in Figs. 5, 6, and 10 I have shown a well-known mechanism of the kind—namely, a rotary shuttle S, driven by a crank-shaft S', connected by a connecting-rod s' with the main driving-shaft w—and these devices form no part of my invention, 15 but are necessary to the proper formation of the binding and barring stitches.

The binding mechanism.—Referring to Figs. 5 and 7, on one side of the overhanging arm M' is arranged to revolve in suitable bearings 20 a shaft w', parallel with but below the main driving-shaft w, said shaft w' carrying a gear-wheel r' in gear with the wheel r on main shaft w. The shaft w' also carries a sleeve f', that has a cam or irregular groove f², so constructed as to impart a rocking motion to the 25 vertical arm f³ of an angle-lever F, presently to be referred to. At its forward end, which projects beyond the head M of the machine, the shaft w' carries a cam g', Fig. 7, and at 30 its rear end a cam-disk a of such construction or provided in its rear face with a cam groove of such construction as to impart a rocking motion to the vertical arm a' of a rock-lever A. The needle-bar B has free 35 vertical motion in bearings in a pendulous plate g, said plate being suspended from a pin 22 on the machine-head M and having a lateral projection g², that carries a pin on which is mounted a roller in the path of the 40 greater diameter of the aforementioned cam g', the latter being of variable diameter, so as to alternately move the pendulous plate toward the right, Fig. 7, and then release the same, said plate being moved in the opposite 45 direction or toward the left by a spring g³, which also acts as a buffer for said plate and needle-bar. It will be seen that when shaft w' is revolved through main shaft a vibrating motion in a direction across the bed-plate 50 is imparted to the needle-bar and needle. The work-holder comprises two plates h⁴ d⁵, Fig. 7, said plate h⁴ having motion in a direction at right angles to the longitudinal axis of the bed-plate G, while plate d⁵, which is the 55 work-supporting plate and hereinafter referred to as the "work-plate," has motion with such plate h⁴ and independently of said plate in the direction of the length of said bed-plate. The work is held to the work-plate by 60 means of a suitable clamping device comprising a lever D, pivoted about centrally on a lateral extension d¹⁵ of the work-plate d⁵, said lever carrying at the outer or free end of its arm d⁶ a work-clamp d⁷ of suitable construction that coöperates with the work-plate d⁵ to hold and impart the necessary movements to the work. The clamp d⁷ is held down

to the work by a spring d⁸, acting on an arm d¹⁰ of the clamp-lever D, said arm being guided on a pin d⁹, that passes through the 70 extension d¹⁵ of the work-plate d⁵ and through the bed-plate G. The lower end d¹⁹ of said pin, which is bent at right angles, Fig. 9, is engaged by the free end of the arm l of an angle-lever L, by means of which the clamp-lever 75 can be lifted off the work-plate.

On the under side of the bed-plate G is arranged a ratchet-wheel a⁵, Figs. 9 and 12, that is revoluble on a journal j, secured to said bed-plate. The rock-lever A, hereinbefore referred to and rocked by the cam-disk a on shaft w', has its lower arm connected by a segmental connecting-rod a², Figs. 5, 6, and 9, with a pawl-supporting bar a³, which receives from lever A, through connecting-rod 80 a², a rectilinear reciprocating motion, said bar being guided in suitable brackets on the underside of the bed-plate G. To the bar a³ is pivoted a pawl-arm a⁴, to which is detachably connected, by means of a screw pin or bolt and a nut 6, a pawl 5, that is normally held in engagement with the teeth of the ratchet-wheel a⁵ by a spring a⁶. The pawl a⁴ has its face or edge proximate to the ratchet-wheel a⁵ inclined rearwardly and outwardly or away 85 from said ratchet-wheel, and upon said inclined face bears a pin i⁰ on the arm 7 of a bell-crank lever i'. It will readily be seen that as the shaft w' is revolved by the main shaft w through the gearing r r' described and 90 the lever A is rocked to and fro by the cam-disk a on said shaft w' the pawl-supporting bar a³ is reciprocated. During the forward movement of the bar a³ the pawl 5 moves over the teeth of the ratchet-wheel a⁵ without revolving the same; but during the backward movement of said bar the said pawl acts positively on wheel a⁵ and revolves the same, and inasmuch as the lever i' is immovable, as hereinafter explained, the said 95 pawl as it moves along the pin i⁰ will be disengaged from the teeth of the ratchet-wheel a⁵ after it has revolved the same a certain distance. The pawl-arm a⁴ is adjustable relatively to the ratchet-wheel for the purpose 100 of varying within certain limits the amplitude of the step-by-step rotations of said wheel and for the purpose of holding the pawl 5 out of engagement with the wheel when this is desirable or necessary. To these ends 105 the vertical arm 7^a of lever i', which is fulcrumed at 8, is connected to a wing-nut N on the outer cylindrical screw-threaded end of a bar i, Figs. 6 and 9, a coiled spring being mounted on said cylindrical portion of 110 the bar between the nut and an enlarged portion of such bar, whose rear end is pivoted to a swinging arm i², itself pivoted to a suitable bracket i³ at the rear end of the machine, Fig. 5. The bar i has a lock-notch 14, 115 that is engaged by a spring-actuated catch or locking-pawl I, whose arm i⁸ extends laterally beyond the bed-plate and has its end bent up to serve as a handhold for moving 120

said catch out of engagement with the lock-notch 14 in said bar *i*, Fig. 8. The bar *i* has a lateral slotted projection 12, Figs. 6 and 9, into the slot of which projects the short arm *i*⁶ of a hand-lever *I*', fulcrumed in a suitable bracket *i*⁷ on the underside of the bed-plate *G*, the longer arm *i*⁵ of said lever *I*' projecting through the bed-plate, Fig. 5. It is obvious that by manipulating the wing-nut *N* the bell-crank lever *i*⁷, and therethrough the pawl-arm *a*⁴, can be adjusted with great nicety, the spring *i*² acting as a yielding abutment for the nut, and such adjustment can be effected without disengaging the catch *I* from the lock-notch in bar *i*. If, however, it becomes desirable or necessary to throw the pawl 5 instantaneously out of engagement with the ratchet-wheel *a*⁵, this may be effected by moving said catch out of engagement with the lock-notch 14 in bar *i* with one hand and by moving the long arm *i*⁶ forwardly with the other hand, the bar *i* being moved backward and the bell-crank lever so actuated as to move the pawl-arm (through the pin *i*⁹) on said lever 5 away from the ratchet-wheel *a*⁵, said parts remaining in this position until the arm *i*⁶ of lever *I*' is moved back again to a vertical position.

On its upper face the ratchet-wheel *a*⁵ has a discoidal raised portion *a*⁷, Figs. 12 and 13, in which is formed a heart-shaped groove *a*⁸, engaged by a roller 21 on a pin *b*' at the free end of an angle-lever *b*, (also shown in dotted lines in Fig. 6.) The lever *b* is fulcrumed on a stud *b*² on the under side of the bed-plate *G* and has a segmental slot *b*³, into which extends a pin *b*⁷ at the inner end of a connecting plate or bar *c*, that is coupled to a bar *c*², connected to a pin *c*²², secured to and depending from the work-plate *d*⁵. The connecting plates or bars *c*² and *c* are coupled together by means of a coupling-pin *c*', that fits suitable holes in said plates, said pin *c*' having a head engaged by the free end of a spring *c*⁴, secured to the under side of plate *c*², the tendency of the spring *c*' being to throw the pin *c*' downward out of engagement with the plates *c*² *c*. The pin *c*' is normally held in engagement with the plates *c*² *c* by a bearing-plate *c*³, that has a foot *c*⁷, guided in a suitable bracket *c*⁸, and from said foot *c*⁷ projects a pin *c*⁹, that extends through a hole in the end of one of the arms of a two-armed lever *c*⁵, Fig. 9, (also shown in dotted lines, Fig. 6,) for purposes hereinafter explained.

An arm *b*⁴, provided with a segmental slot *b*⁵, is so arranged relatively to the lever *b*, hereinabove described, that a screw-pin *b*⁶ at the angle of said lever extends through the segmental slot *b*⁵, so that by means of a nut provided with a suitable handle *b*¹⁵, Figs. 6 and 12, the said lever *b* can be rigidly connected with said arm *b*⁴. It will be seen that the amplitude of the reciprocating movements of the connecting-plate *c* can be varied within certain limits by adjusting the pin *b*⁷ or both

pins *b*⁶ and *b*⁷ in their respective slots *b*⁵ *b*³ in arm *b*⁴ and lever *b*.

The mechanism so far described serves to sew or bind the edges of a buttonhole, and this, as well as the barring of one or both ends of such buttonhole, may be effected either before or after the buttonhole is cut, as will be readily understood, the fabric being placed on the work-plate *d*⁵ so that the buttonhole 75 will lie in the plane of the driving-shafts *ww'*, with the left-hand end of such buttonhole in the path of the needle. The driving-shaft being rotated in the usual manner, the needle-bar *B* will be reciprocated and at the same time 80 vibrated, while the work-holding devices—*i. e.*, the work-plate *d*⁵ and work-clamp *D*—will receive a step-by-step progressive or feed motion toward the left end of the machine through one half—say, the half *a*¹⁸, Figs. 6 85 and 12—of the heart-shaped groove *a*⁸ in the raised portion *a*⁷ of ratchet-wheel *a*⁵ and through the step-by-step rotation of such ratchet-wheel, said heart-shaped groove acting upon the roller 21 on lever *b*, and through 90 the described connections—*i. e.*, the plates *c* *c*² on work-plate *d*⁵—and as the clamping-lever *D* is carried by said work-plate *d*⁵ and is free to move either toward the right or left in the plane of the main driving-shaft the 95 said devices and the work are moved step by step toward the left end of the machine, as stated, thereby binding one edge of the buttonhole. When the binding of one edge is completed and as the roller is about to enter 100 the other half of the heart-shaped groove, it becomes necessary to stop the operation of the binding mechanism and throw the barring mechanism into operation.

Stop and uncoupling mechanism.—On the 105 face of the ratchet-wheel *a*⁵ are two segmental raised portions *a*⁹, diametrically opposite each other, and in the path of said segmental projections lies a roller *e*' on the lower horizontal arm *e* of an angle-lever *E*, Figs. 5, 9, and 12, (also shown in dotted lines in Fig. 6,) said lever being fulcrumed to a suitable bracket 20 on the under side of the bed-plate *G*, the vertical arm *e*⁵ of which lever is connected to one end of a push-bar *e*⁶, Fig. 5, whose opposite end is pivotally connected with a lock-rod *e*¹⁷, that has a conical locking-head *e*⁷, Fig. 7, which normally lies in front of a recess *g*⁷ in the pendulous plate *g* for the needle-bar *B*. The arrangement of these parts is such that as the roller 21 of lever *b* is about to enter the other half of the heart-shaped groove referred to the said roller *e*' on arm *e* of lever *E* rides upon one of the projections *a*⁹, thereby moving the arm *e*⁵ of said lever *E* backward, 115 drawing the lock-bar *e*¹⁷ along and bringing its head *e*⁷ into engagement with the recess in the pendulous plate *g*, thereby stopping the vibrations thereof. Simultaneously there-with the said arm *e* of lever *E*, which is provided with a pin *e*⁹, that extends through the arm *c*²⁵ of the lever *c*⁵, hereinbefore referred

to, raises said arm c^2 against the stress of the spring e^x , bearing on pin e^0 , Fig. 9, and depresses the arm c^4 of said lever c^5 , and as this arm is connected, through the pin e^0 , with the 5 foot of the pressure-plate c^3 , Fig. 13, said plate is depressed, thereby permitting the spring c^4 to move the coupling-pin c' out of engagement with plates c^2 and c , and consequently with lever b , thus stopping the step- 10 by-step feed movement of the work-plate d^5 and therewith that of the work-clamp D. Simultaneously with these operations the clamp D and the work-plate must be so connected as to form barring-stitches at the left 15 end of the buttonhole.

Barring-stitch and coupling mechanism.—The arm e of lever E has a plate-like projection e^2 , Figs. 9, 12, and 13, (also shown in dotted lines in Fig. 6,) on which bears a coupling-pin e^4 , that is guided in a sleeve e^3 , depending from the bed-plate G, and is adapted to be moved through a longitudinal slot in a lever f , fulcrumed at f^x to the upper face of the bed-plate G, Fig. 8, and through a transverse slot d^2 in plate d' , hereinbefore referred to as secured to the extension d^{15} of the work-plate d^5 . As the arm e of lever E is lifted in riding onto one of the projections a^9 on the face of ratchet-wheel a^5 , as above described, 25 the plate-like projection e^2 pushes the pin e^4 through a hole in lever f into the slot d^4 of plate d' , thus coupling the work-plate d^5 and the work-clamp to said lever f . This lever f is connected by a bar f' , Fig. 8, with the 30 short arm f^4 of the rock-lever F, hereinbefore mentioned, which lever is rocked by the groove in the sleeve f' on shaft w' , so that the work-holding devices will receive a short reciprocating motion in a plane parallel with 35 the said shaft w' and with the length of the buttonhole.

The discoidal raised portion a^7 on the ratchet-wheel a^5 has on its periphery four shoulders $a^{10} a^{11} a^{12} a^{13}$, arranged diametrically opposite each other in front of the segmental projection a^9 on the face of said ratchet-wheel a^5 , said shoulders $a^{10} a^{11}$ and $a^{12} a^{13}$ being connected by an inwardly-curved face a^{31} .

50 A roller h on the end of an arm h' of a rock-lever II, fulcrumed to the under side of the bed-plate at 41, is held in contact with the periphery of the raised part a^7 of ratchet-wheel a^5 by a coiled spring g^0 exerting power 55 on the free end of the arm h^2 of rock-lever H, Fig. 8. This end of arm h^2 of lever H has a longitudinal slot 40, into which projects a pin h^1 , that passes through a hole in the feed-plate h^4 and through a transverse slot h^0 in 60 the work-plate d^5 , whereby a step-by-step progressive or feed motion in a direction at right angles to the length of the buttonhole is imparted to said feed-plate h^4 without interfering with the reciprocating motion in a 65 direction at right angles to said feed motion of the work-plate d^5 .

It has been stated above that when one edge

of a buttonhole is bound the work-holding devices will be at the limit of their movement toward the left—that is to say, the needle will 70 be above the left end of such buttonhole, its vibrating motion having been arrested, the feed devices uncoupled from the work-holding devices, and the said devices coupled with the feed and reciprocating mechanism there- 75 of, at which moment the roller h or lever II rides over the shoulder a^{10} , whereby the arm h^2 on said lever, and through it the feed-plate h^4 and work-plate d^5 , are moved forward in the direction of arrow v , Figs. 6 and 9, which 80 is necessary, because the barring is commenced on one side of the buttonhole. The roller h will now be acted upon by the inwardly-curved face a^{31} , that connects the two shoulders $a^{10} a^{11}$, whereby the lever-arm h^2 85 will be moved progressively step by step in an opposite direction, (arrow v' , Figs. 6 and 9,) thereby imparting to the work-holding devices the required feed motion during the barring of the left end 3 of the buttonhole. 90 The roller h then comes in contact with shoul- 95 der a^{11} . During this time the work-plate d^5 receives the proper reciprocating motion to form the barring-stitches at said end 3, Figs. 1 and 2, of the buttonhole, the needle having a vertical reciprocating movement only. As the roller h on arm h' of lever II rides over the shoulder a^{11} the arm h^2 of said lever is thrown back in the direction of arrow v to bring the opposite edge of the buttonhole into 100 a proper position relatively to the needle. The described movements of the feed-lever II take place in view of the fact that the point of the shoulder a^{10} , and in fact a portion of the peripheral curved face a^{31} of the raised portion a^7 on ratchet-wheel a^5 , projects beyond the general periphery of said projection— 105 namely, from those peripheral segments which connect the inner edge of shoulder a^{10} with the like edge of shoulder a^{12} and the outer edge of shoulder a^{11} with the like edge of shoulder a^{13} , the raised portion being of a uniform diameter throughout these positions, while said diameter on a line with the outer edge of the shoulders $a^{10} a^{12}$ and along a portion 110 of the inwardly-curved face a^{31} is greater than said common diameter. The moment the roller h on arm h' of lever II reaches the top of shoulder a^{11} the roller e^8 on arm e of lever E rides off the proximate segmental projection a^9 on the face of the ratchet-wheel a^5 , whereby said lever is rocked, so as to move the push-bar forward and disengage the pen- 115 dulous plate g , allowing the needle-bar B to vibrate. The dropping of the lever E also 120 causes the coupling-pin e^4 , Figs. 10 and 11, to drop out of engagement with the plate d' on extension d^{15} of work-plate d^5 and allows the spring e^x to depress the arm c^2 of lever c^5 , and consequently raise the arm c^4 of said lever 125 and with it the pressure-plate c^3 , which latter moves the coupling-pin c' against the stress of its spring c^4 again into engagement with the plates c^2 to couple them together, Fig. 130

13, and consequently with the feed-lever *b*, whose roller now enters the second half of the heart-shaped groove *a*⁸ in the raised portion *a*⁷ on the ratchet *a*⁵, so that the parts are again in their respective positions necessary to the binding of the opposite edge of the buttonhole. Inasmuch as the two halves of the heart-shaped groove *a*⁸ are symmetrical, the work-holding devices will again receive a step-by-step or feed movement, but in a reverse direction—namely, toward the right—until said opposite edge is bound, when the work may be removed. If, however, the opposite edge *3*^a is also to be bound, then as soon as the work reaches the limit of its feed motion toward the right the uncoupling of the feed devices and the vibration of the needle-bar are stopped, the work-holding devices are coupled to the lever *f* and rock-lever *F*, and the feed-lever *H* is then operated by the shoulders *a*¹² *a*¹³ and the feed - surface *a*³¹, connecting the same, substantially as above described; but as in this case the fabric and work-holding devices will have been moved to the limit of their movement toward the right the slot *d*² in the plate *d*' on the extension *d*¹⁵ of the work-plate *d*⁵ will be out of reach of the pin *e*⁴, so that the levers *f* and *F* could not be coupled to the work-plate, and to effect this the said plate *d*' has a comparatively large opening 17, Figs. 10 and 11, and into said opening is fitted a projection on a small plate *d*⁸ for the reception of the aforesaid coupling-pin *e*⁴. The plate *d*⁸ is T-shaped and has in its head a longitudinal slot 19, so that said plate can be adjusted toward or from the vertical axis of the coupling-pin *e*⁴ in accordance with the length of the buttonhole to be barred at both ends, so that when the work - holding devices have reached the limit of their movement toward the right the socket in the under side of the projection of the adjustable plate *d*⁸ will lie in the plane of motion of the said coupling-pin *e*⁴, whereby the parts are coupled together, as before and for the purposes stated, as will be readily understood.

Having thus described my invention, what I claim as new therein, and desire to secure by Letters Patent, is—

1. In a buttonhole-sewing machine, the combination with suitable stitch-forming appliances and a work-holder, of means for imparting to the needle-bar first a vibrating motion in a direction at right angles to the length of the buttonhole in addition to its vertical reciprocating motion, and to the work-holder a progressive motion lengthwise of the buttonhole, next a vertical reciprocating motion only to the needle-bar, and to the work-holder a reciprocating motion lengthwise of the button-hole, and simultaneously therewith a progressive motion in a direction at right angles to such buttonhole, whereby one edge of a buttonhole is bound and one end barred by stitches laid parallel or approximately parallel with said edge, as set forth.

2. In a buttonhole-sewing machine, the combination with suitable stitch-forming appliances and a work-holder, of means for imparting to the needle-bar first a vibrating motion in a direction at right angles to the length of the buttonhole in addition to its vertical reciprocating motion, and to the work-holder a progressive motion lengthwise of the button-hole, next a vertical reciprocating motion only to the needle-bar, and to the work-holder a reciprocating motion lengthwise of the buttonhole, and simultaneously therewith a progressive motion in a direction at right angles to such buttonhole, whereby one edge of a buttonhole is bound and one end barred by stitches laid parallel or approximately parallel with said edge, and means whereby these operations are repeated and the direction of the progressive feed movements of the work-holder lengthwise and crosswise of the buttonhole are reversed thereby binding the other edge and similarly barring the other end of such buttonhole.

3. In a buttonhole-sewing machine, the combination with the stitch-forming devices, the work holding and guiding appliances and mechanism for imparting a vibrating motion to the needle-bar in addition to its vertical reciprocating motion; of mechanism actuating the work holding and guiding appliances to feed the work along as the stitching proceeds, a stop mechanism for stopping the vibratory movement of the needle-bar without stopping its vertical reciprocating motion, and mechanism for imparting to the work through the work holding and guiding appliances a progressive movement and simultaneously therewith a reciprocating movement in a direction at right angles to said progressive movement, and means for adjusting the movements of the work-holder relatively to the length of the buttonhole, substantially as and for the purposes set forth.

4. In a buttonhole-sewing machine, the combination with the work-plate *d*⁵, of the ratchet-wheel *a*⁵ provided with a cam-groove in one of its faces, a lever provided with a pin projecting into said cam-groove and mechanism adapted to operate automatically and periodically to connect and disconnect the work-plate from said lever, for the purpose set forth.

5. In a buttonhole-sewing machine, the combination with the work-plate *d*⁵, an actuating-lever, connections between the two, mechanism adapted to automatically and periodically disconnect the lever from the plate, and the ratchet - wheel *d* having a heart-groove in which the free end of said lever works, of adjusting devices for adjusting the amplitude of the movements of the lever, for the purpose set forth.

6. In a buttonhole-sewing machine, the combination with the stitch-forming devices, the work holding and guiding appliances and mechanism for imparting to the needle-bar a vibrating motion in addition to its vertical

- reciprocating motion; of mechanism acting upon said work holding and guiding appliances to feed the work along as the stitching progresses, a stop mechanism acting upon the 5 needle-bar to stop its vibration, and mechanism acting upon the work holding and guiding appliances to impart to the work a progressive movement and simultaneously therewith a reciprocating movement at right angles to such progressive movement, said mechanisms operating automatically and alternately, whereby one edge of a buttonhole may be first sewed or bound, then one end of such buttonhole stayed by stitches laid substantially at right angles to the binding-strokes, after which the other edge, and opposite end of said buttonhole can be sewed and stayed in a similar manner without interruption, substantially as set forth.
- 20 7. In a buttonhole-sewing machine, the combination with the needle-bar, mechanism for reciprocating the same vertically, a pendulous bearing for and in which said bar has free vertical motion, and mechanism for vibrating said bearing; of a stop mechanism comprising an endwise-movable rod provided with a stop at one end adapted to engage the vibratory bearing and stop the vibrations thereof, and an actuating-lever connected 25 with said rod and set in motion by a revolute element of the machine to move such rod in one or the other direction, for the purpose set forth.
- 30 8. In a buttonhole-sewing machine, the combination with the work-support, appliances for imparting to said support a steady progressive or feed motion in one or the other direction, and a connection between said support and appliances; of a coupling for coupling the support to such connection, and means for automatically uncoupling the same, for the purpose set forth.
- 35 9. In a buttonhole-sewing machine, the combination with the work-support, appliances for imparting to said support a steady progressive or feed motion in one or the other direction, and a connection between said support and appliances; of a coupling for coupling the support to such connection, means 40 for automatically uncoupling the same, and mechanism for imparting to the support a reciprocating motion when uncoupled from the feed devices, for the purpose set forth.
- 45 10. In a buttonhole-sewing machine, the combination with the work-support, the feed-lever b , the connecting-plate c' , the coupling-pin c' , the spring c^4 exerting pressure on said pin to move the same out of engagement with said plate and lever; of a bearing acting 50 forcibly upon the pin against the stress of its spring to hold said pin in engagement with the aforesaid plate c' and lever b , substantially as and for the purpose set forth.
- 55 11. In a buttonhole-sewing machine, the combination with the work-support, the feed-lever b , the connecting-plate c' , the coupling-pin c' , the spring c^4 exerting pressure on said

pin to move the same out of engagement with said plate and lever; of a bearing acting forcibly upon the pin against the stress of its 70 spring to hold said pin in engagement with the aforesaid plate c' and lever b , and mechanism connected with and operating to move said bearing away from the pin and allow the latter to uncouple said plate c' from lever b , 75 substantially as and for the purpose set forth.

12. In a buttonhole-sewing machine, the combination with the work-support, mechanism for imparting thereto a progressive or feed motion, a spring-controlled coupling-pin 80 coupling said support to said mechanism, and appliances operating automatically to uncouple said parts by withdrawal of the pin; of mechanism for imparting to the work-support a reciprocating and a simultaneous progressive or feed motion in directions at right angles to each other immediately after the withdrawal of the coupling-pin, for the purpose set forth.

13. In a buttonhole-sewing machine, the combination with the work-support, mechanism coupled thereto for imparting a progressive or feed motion to such support, and appliances for uncoupling the support from said mechanism, the shaft w' , the cam-sleeve f' 95 thereon, the lever F vibrated by said sleeve, the lever f connected with and vibrated by lever F , a coupling-pin adapted to couple the work-support and lever together, and means for moving said pin into and out of engagement with said parts; of the ratchet-wheel a^5 provided with a cylindrical raised portion a^7 having shoulders $a^{10} a^{11} a^{12} a^{13}$ connected by cam-surfaces, and a lever acted upon by said shoulders and cam-surfaces and connected 100 with the work-support whereby a reciprocating motion is imparted to said support and a simultaneous progressive or feed motion in one or the other direction, substantially as and for the purpose set forth.

14. In a buttonhole-sewing machine, the combination with the slotted plate d' of the work-support and the socketed plate d^3 adjustable in the slot of said plate, the slotted lever f , the coupling-pin e^1 adapted to be 110 moved through the slot of said lever into a second slot in the aforesaid plate d' , and the lever E constructed as described to act on said pin; of the step-by-step rotatable ratchet-wheel a^5 having segmental projections a^9 on its upper face in the path of a roller on said lever E , substantially as and for the purpose set forth.

15. In a buttonhole-sewing machine, the combination with the slotted plate d' on extension d^{15} of work-plate d^5 , said plate d' having a slot d^2 and opening 17, the socket-piece d^3 adjustable in said opening 17, and a slotted vibrating lever; of a coupling-pin and mechanism operating to periodically and alternately move said pin through the slot in the lever and the slot d^2 in work-plate d' or into the socket-piece d^3 thereon, for the purpose set forth.

16. In a buttonhole-sewing machine, the combination with the push-bar e^6 , the lever E having arm e carrying a roller e' ; of the ratchet-wheel a^5 provided with segmental pro-

5 jections a^9 in the path of the aforesaid roller, for the purpose set forth.

17. In a buttonhole-sewing machine, the combination with the push-bar e^6 , the lever E having arm e carrying a roller e' and a spring-
10 controlled laterally-projecting pin e^0 , and the ratchet-wheel a^5 provided with segmental pro-

jections a^9 in the path of the aforesaid roller; of the lever e^5 engaged by the aforesaid pin, and the mechanism operated by said lever e^5 , for the purpose set forth.

15 In testimony whereof I hereunto sign my name, in the presence of two subscribing witnesses, this 9th day of September, 1896.

JULIUS GUTMANN.
